(57) **CLAIM**

The ornamental design for a divider as shown and described.

DESCRIPTION

FIG. 1 is a front perspective view of a divider showing my new design;

FIG. 2 is a front elevational view of the divider of FIG. 1;
FIG. 3 is a rear elevational view of the divider of FIG. 1;
FIG. 4 is a left side plan view of the divider of FIG. 1;
FIG. 5 is a right side plan view of the divider of FIG. 1;
FIG. 6 is a top plan view of the divider of FIG. 1;
FIG. 7 is a bottom plan view of the divider of FIG. 1; and
FIG. 8 is a cross-sectional view of the divider, taken at plane
8-8 of FIG. 2, with the arrows extending therefrom indicating
the direction of sight.
